(57) **CLAIM**

The ornamental design for a wafer support of semiconductor
manufacturing apparatus, as shown and described.

DESCRIPTION

FIG. 1 is a front, top and right side perspective view of a
wafer support of semiconductor manufacturing apparatus
showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view taken along line **8-8** in FIG.
2 thereof;

FIG. 9 is an enlarged cross-sectional view taken along line
9-9 in FIG. **2** thereof;

FIG. 10 is an enlarged cross-sectional view taken along line
10-10 in FIG. **2** thereof; and,

FIG. 11 is an enlarged view taken from the broken line box
labeled **11** in FIG. **1**.

The broken lines in FIG. **1** and FIG. **11** show the boundary
of the enlarged portion views and form no part of the
claimed design.
